[57] CLAIM

The ornamental design for a combined motion detector
and lamp controlled thereby, as shown.

DESCRIPTION

FIG. 1 is a front view of a combined motion detector
and lamp controlled thereby showing our new design;
FIG. 2 is a rear view thereof;
FIG. 3 is a right side view thereof;
FIG. 4 is a left side view thereof;
FIG. 5 is a top plan view thereof; and
FIG. 6 is a bottom plan view thereof.
